UNITED STATES PATENT OFFICE.

MOSES STEINER, OF BLUFFTON, OHIO.

HOUSE.

1,215,740.

Specification of Letters Patent.

Patented Feb. 13, 1917.

Application filed July 3, 1916. Serial No. 107,429.

To all whom it may concern:

Be it known that I, MOSES STEINER, a citizen of the United States, residing at Bluffton, in the county of Allen and State of Ohio, have invented certain new and useful Improvements in Houses, of which the following is a specification.

My invention relates to improvements in a knock-down house, adapted for use as a chicken coop, chicken brooder, or the like.

An important object of the invention is to provide a house of the above mentioned character, formed of parts which may be readily separated, and arranged in a compact manner for shipment, and securely held together in such compact manner.

A further object of the invention is to provide means whereby the floor of the house may be readily removed for the purpose of cleaning the same.

A further object of the invention is to provide ample shade means whereby the chickens are protected from the sun.

Other objects and advantages of the invention will be apparent during the course of the following description.

In the accompanying drawings forming a part of this specification and in which like numerals are employed to designate like parts throughout the same,

Figure 1 is a front side elevation of a house embodying the invention, with the curtain in the closed position.

Fig. 2 is a similar view, with the curtain rolled up,

Fig. 3 is an end elevation of the same,

Fig. 4 is a front side elevation, with the end members elevated,

Fig. 5 is a horizontal sectional view taken on line 5—5 of Fig. 3,

Fig. 6 is a vertical longitudinal sectional view taken on line 6—6 of Fig. 3,

Fig. 7 is a transverse sectional view taken on line 7—7 of Fig. 2,

Fig. 8 is a perspective view of one end of the house, showing the parts separated, and,

Fig. 9 is a front elevation of the apparatus, with the parts separated and arranged in a compact manner, for shipment.

In the drawings, wherein for the purpose of illustration is shown a preferred embodiment of my invention, the numeral 10 designates the body portion of the house as a whole, comprising a forward side-member

11 and a rear side-member 12. The forward side-member is preferably in the form of a rectangular frame covered with wire screening 13. This side-member is provided with a door opening adapted to be covered by a sliding door 14, as shown. The forward side-member 11 has interior vertical legs 15 rigidly secured thereto and projecting above and below the same, for a substantial distance, but extending above the same for a much greater distance. The rear side-member 12 is preferably imperforate and has interior vertical legs 16 rigidly attached thereto, which extend above and below the same for a substantial distance, as shown. As more clearly shown in Figs. 6 and 7, the side-members 11 and 12 are provided at their bottoms with interior horizontal floor supporting bars or members 17 and 18 respectively, which are rigidly attached thereto, for a purpose to be described. The forward side-member 11 has a vertical grooved guide element 19 attached to the inner side thereof and the rear side-member 12 has a corresponding vertical grooved guide element 20, secured to the interior thereof. These guide elements are adapted to receive a transverse partition 21, which is adapted to be inserted between and removed therefrom by an upward movement. When arranged within the guide elements the partition 21 rests upon and is supported by the bars 17 and 18, as shown. The partition 21 has a door opening 22, adapted to be covered and uncovered by a movable door 23 of any well known or preferred construction. It is apparent that the partition 21 divides the body portion of the house into two chambers and there are separate floor sections 24 and 25. These floor sections are arranged upon opposite sides of the partition 21 and are supported by the bars 17 and 18 and are adapted to be moved longitudinally into and out of operative position when the ends of the house are open.

The numeral 26 designates a permanently assembled top portion, comprising a forward side portion 27, a rear side portion 28, tapered end portions 29, and a top or roof 30 which are rigidly secured together in a permanent manner. The forward side portion 27 is in the form of an open frame, covered with the section of wire mesh 31. The top portion 26 is arranged upon the side-

members 11 and 12 and the vertical legs 15 and 16 of these side-members project upwardly into the corners of the top portion 26, thus serving to hold the assembled parts together.

5 The numeral 32 designates end members as a whole, to the interior of which and at their ends are secured pairs of locking bars 33, 34; 35, 36. The forward locking bars 10 33 and 34 are adapted to receive therebetween the ends of the side portions 11 and 27, the bar 33 being arranged upon the exterior thereof while the bar 34 extends interiorly thereof and contacts with the leg 15. 15 The rear bars 35 and 36 are arranged upon the opposite sides of the rear side-member 11, in a similar manner. Attached to the outer side of the end member 29 are hinge elements 37, having knuckles for pivotally 20 and detachably receiving pintles 38 carried by coacting hinge members 39 rigidly attached to the end member 32. When this end member is swung to approximately a vertical position so that the locking bars 25 engage the forward and rear side members, it is obvious that the pintles 38 may be inserted within or removed from the knuckles of the hinge members 37. The side-members 32 may assume vertical positions for closing 30 the ends of the chambers of the house or more or less horizontal positions, as shown in Fig. 4, thus opening the ends of the chambers. The end-members may be retained in the approximately horizontal position by means of chains 39', detachably secured thereto. As clearly shown in Fig. 2, the end-members 32 carry hooks 40, adapted for detachable engagement with eyes 41, rigidly secured to the forward and side 35 members 11 and 12.

40 The numeral 42 designates a curtain, formed of canvas or the like, having one end attached to a rod 43, which is pivoted at its ends to the top portion 26, as shown at 44. 45 The lower end of the curtain 42 has connection with a rod 45, carrying hooks 46 at their ends. The curtain is adapted to be rolled upon the rod 45 and when the curtain is unrolled the same may be moved 50 downwardly to assume a vertical position and the hooks brought into engagement with eyes 47, attached to the end-members 32, as shown. This curtain then serves to close the screen covered forward side-member of the 55 house.

55 Mounted to reciprocate within sockets 48 rigidly attached to the end-members 29 are supporting bars 49, carrying eyes 50 at their forward ends, adapted for engagement with 60 the hooks 46 carried by the rod 45. When the bars 49 are moved forwardly as indicated in Fig. 3, and the hooks 46 engage the eyes 50, the curtain will project forwardly in a substantially horizontal position, thus 65 providing a shade curtain.

As clearly shown in Fig. 9, the top portion has its forward and rear sides 27 and 28 provided with eyes 51 for engagement with the hooks 40, when the end-members 32 are arranged upon the top member 26, the 70 latter being inverted.

In assembling the different parts of the house, the forward and rear side-members 11 and 12 are first arranged in a suitably spaced parallel relation and the partition 21 75 inserted in the grooved guides 19 and 20. The top member 26 is then placed upon these side-members and the legs 15 and 16 project upwardly into the corners of the top member 26. The floor portions 24 and 80 25 are now moved horizontally through the open ends of the chambers to the operative position. The end-members 32 are brought into proximity to the ends of the assembled side-members 29, and while suitably raised, 85 the pintles 38 are inserted into the knuckles of the hinge members 37, for pivotally connecting the end-members 32 to the end portions 29. These end-members are then swung downwardly to assume a substantially vertical position, and the locking bars 33, 34; and 35, 36 will serve to securely bind the forward and rear side-members 11 and 12 to the top member 26.

When it is desired to disconnect the several parts of the house for shipment, the same are separated, as is obvious, and all of the parts arranged within the inverted top member 26, except the end-members 32. These end-members 32 are arranged upon 100 the top of the inverted top member 26, and are locked thereto by inserting the hooks 40 in the eyes 51, the locking bars engaging upon opposite sides of the forward and rear side-members 11 and 12. These end-members 32 thus serve as means to retain the separated parts of the apparatus within the top member 26. It is thus apparent that the different parts of the house may be separated and arranged in a comparatively compact and flat manner for shipment.

105 In the use of the apparatus, the curtain 42 may be arranged vertically or horizontally, as hereinabove explained. When it is desired to provide additional shade for the 115 chickens, the end-members 32 may be swung upwardly to assume a more or less horizontal position. When the end-members are in this open position the floor portions 24 and 25 may be readily removed for the purpose of cleaning the same. It is obvious that the house is in no sense restricted to any particular use, in raising chickens or the like, as such use may be widely varied as 120 may be found advantageous.

125 It is to be understood that the form of my invention herewith shown and described is to be taken as a preferred example of the same, and that various changes in the shape, size, and arrangement of parts may be re- 130

sorted to without departing from the spirit of the invention or the scope of the subjoined claims.

Having thus described the invention, I 5 claim:

1. In a house of the character described; side-members provided near their ends with legs projecting above the same for a substantial distance; a top member comprising side and end portions for arrangement upon the side-members and adapted to receive the legs; and end-members provided at their ends with pairs of spaced locking bars, to receive the side-members and the side portions of the top member.
2. In a house of the character described; side-members provided near their ends with transverse elements projecting above the same for a substantial distance; a top member comprising side and end portions for arrangement upon the side-members and adapted to receive the transverse elements; and end-members carrying devices adapted to engage with the side-members and the side portions of the top member.
3. A house of the character described, comprising; side-members provided near their ends with transverse elements projecting above the same for a substantial distance; a top member comprising side and end portions for arrangement upon the side-members and adapted to receive the upper ends of the transverse elements; and end-members hinged to the end portions of the top member and carrying near their ends pairs of spaced locking bars adapted to receive therebetween the ends of the side-members and the ends of the side portions of the top member.
4. In a house of the character described; side-members provided near their ends with transverse elements projecting above the same for a substantial distance; floor supporting elements arranged upon the inner side of the side-members and secured thereto; a floor removably mounted upon the floor supporting elements and adapted to be moved longitudinally through one end of the house; a top member comprising side and end portions for arrangement upon the side-members and adapted to receive the upper ends of the transverse elements; and

end-members having detachable hinged connections with the end portions of the top member and carrying near their ends pairs 55 of spaced locking bars adapted to receive therebetween the ends of the side-members and the ends of the side portions of the top member.

5. In a house of the character described; 60 side-members; a top member comprising side and end portions for arrangement upon the side-members; and end-members connected with the end portions of the top member and carrying pairs of spaced locking bars adapt- 65 ed to receive therebetween the side-members and the side portions of the top member.

6. In a house of the character described; a top member comprising permanently as- 70 sembled side and end portions; side-mem- bers carrying transverse elements extending at their upper ends upwardly beyond the side members and adapted for insertion within the top member; end-members pro- 75 vided at their ends with pairs of transverse locking bars adapted to receive therebetween the side-members and side portions of the top member when the different parts of the house are assembled and to receive the longi- 80 tudinal edges of the side portions of the top member when the top member is inverted for receiving other elements of the house and the end-members arranged thereon; and means for detachably and pivotally connect- 85 ing the end-members with the end portions of the top member.

7. In a house of the character described; side-members provided with approximately horizontal floor supporting bars; a top mem- 90 ber having detachable connection with the side-members; a partition removably mount- 95 ed between the side-members to form a plu- rality of chambers; floor sections movably mounted upon the floor supporting bars and arranged upon opposite sides of the parti- tion; and end-members hinged to the top portion and adapted to be moved to opened and closed positions.

In testimony whereof I affix my signature in presence of two witnesses.

MOSES STEINER.
